E. F. Eaton -

INVENTOR.

Frederick W. Stelling.

BY
Arthur B. Perkins.
ATTORNEY.

UNITED STATES PATENT OFFICE.

FREDERICK W. STELLING, OF HARTFORD, CONNECTICUT.

TARGET.

1,281,687.

Specification of Letters Patent. Patented Oct. 15, 1918.

Application filed April 20, 1916. Serial No. 92,415.

To all whom it may concern:

Be it known that I, FREDERICK W. STELLING, a citizen of the United States, and a resident of Hartford, in the county of Hartford and State of Connecticut, have invented a new and Improved Target, of which the following is a specification.

My invention relates more especially to the class of targets used upon comparatively short ranges, as in buildings and similar places, and an object of my invention, among others, is to produce a structure that shall be comparatively inexpensive to make and that shall be particularly efficient in use.

One form of structure embodying my invention, and in the construction and use of which the objects herein set out, as well as others, may be attained, is illustrated in the accompanying drawings, in which—

Figure 1 is a side view of my improved structure shown as broken away at the center.

Figs. 2 and 3 are detail side and top plan views, scale enlarged, showing the construction of my improved apparatus.

Fig. 4 is a detail view, in cross section, on plane denoted by dotted line 4—4 of Fig. 2.

Figs. 5 and 6 are detail side and top plan views of the movable holder.

In the accompanying drawings, the numeral 7 denotes one of the uprights, of which there are preferably two, located one at each end of a butt plate 8, the latter being preferably constructed of metal and ex-

tending across from one to the other of the uprights. An anchor 9 is secured to the butt plate, in the form shown, this being in the nature of a screw-eye held in place by nuts, and with one end of a track cable se-

cured thereto in any suitable manner. A buffer 11 of rubber or any other elastic or resilient material is mounted upon the cable and a receiver 12 is located to receive a carrier traveling along the track cable. In the

preferred form of construction, and as shown herein, this receiver is of U-shape, its arms being located on opposite sides of the cable and the shank of the screw-eye passing through the base of the receiver and having a nut to secure the receiver in place.

The track cable 10 is secured at its end

opposite the butt plate to a holder 13 that is movably supported by a post 14 located at the firing point. This holder is formed in the shape of a frame having side parts 15 and a handle 16. The cable is secured to a pin 17 between the side parts, said pin also serving to secure the free ends of the side parts together. The post 14 extends upwardly between the side parts, and a sheave 18 is mounted between the side parts to rest against the edge of the post that serves as a track for the holder. The holder may be located in different positions upon the post, as shown in full and dotted lines in Fig. 1 of the drawings, and it may be retained in these different positions in any suitable manner. In the structure herein shown notches 19 are located at intervals along the edge of the post to receive the sheave 18, and the track cable 10 will be sufficiently taut to draw the sheave into the notches and retain it therein. A handle lever 20 with a handle 21 is pivotally secured between the side parts 15 of the holder and serves as a means for locating the holder well above the heads of the persons at the firing point.

A target carrier 22 consists of a U-shaped frame having openings in its branches 23 to receive the cable 10. Sheave supports are secured to the base of the carrier frame, each support consisting of posts 24, each having a foot 25 to receive a rivet or like means for securing the side part to the base of the U-shaped frame, and a plate 26 extends across and is secured to the posts at their upper ends. Each of the sheave supports preferably consists of two posts and one plate, there being two of these supports secured to the base of the U-shaped frame of the carrier and each of said supports faces in an opposite direction from that in which the other support faces, as shown in Fig. 3 of the drawing. Supporting sheaves 27 are secured to the plates 26, preferably on the opposite side thereof from that to which the posts 24 are secured to said plate.

A target support 28 is secured to the under side of the carrier, preferably at its lengthwise center and between the sheave supports, this construction stiffening the

base of the target carrier and imparting rigidity thereto. The target support is of U-shape, the ends of its branches having outward feet that serve as a means for attachment of the support to the carrier. A clip 29 is secured to that side of the target support opposite the firing point, the support thus serving the purpose of a shield to the clip and preventing injury such as would result from being struck by bullets. This clip is preferably a spring clip, such as are commonly used as clothes pins and it may be secured in place in any suitable manner and in position to hold the target 30 so that it will be suspended below the support 28. All of the parts are constructed of comparatively thin metal bent into the forms shown and described which enables them to be cheaply constructed and which causes them to be particularly strong and durable.

The branches 23 of the target carrier are so located that they will pass between the arms of the receiver, which arms are flared outwardly, and as the carrier passes between said arms any swaying which it may have is brought to a stop so that the target is held steady.

While I have shown and described herein one form of apparatus embodying my improvements, this may be departed from to a greater or lesser degree and yet be within the spirit and intent of the invention.

I claim—

35 1. A butt, a cable secured at one end to the butt, a target carrier mounted on the table and including a base, sheave supports each consisting of uprights having feet by means of which they are secured to the base and a 40 cross piece uniting the uprights, and sheaves mounted on said cross pieces between the uprights.

45 2. A target carrier for a target apparatus including a U-shaped frame the branches of which have openings to receive a cable, sheave supports each consisting of uprights with feet to receive fastenings to secure the uprights to the base of the support, a plate connecting the upper ends of 50 each pair of supports, sheaves rotatably mounted on said plates, and means for securing a target to the under side of the carrier.

55 3. A carrier for a target apparatus including a U-shaped frame having upwardly extending arms, sheave supports each consisting of two uprights secured to the frame and a cross plate, said supports being located between said arms, sheaves secured to the cross plates, and a U-shaped target support secured to the under side of the frame.

60 4. A target carrier for a target apparatus, said carrier including a U-shaped frame, having upwardly extending arms, a U-

shaped target support secured at about the lengthwise center of the base of said frame, sheave supports each consisting of two uprights located on opposite sides of the target support and with plates secured to the upper ends of said uprights, said supports being located between said arms and sheaves rotatably mounted on said plates.

5. A target apparatus including a cable track, means for raising and lowering one end of the track, a target carrier supported on said cable, a target support depending from said carrier, and a target holder located on that side of the support opposite from said raising and lowering means.

6. A target apparatus including a cable track, means for raising and lowering one end of the track, a carrier movably mounted on said cable, a U-shaped target support depending from said carrier and with its branches located in line lengthwise with the carrier, and a target holder secured to one of the branches of said support on the opposite side thereof from said raising and lowering means.

7. A target apparatus including a cable track, a target carrier supported on and movable from end to end of said cable, a target support depending from said carrier, a butt located at one end of the cable, and a target holder located on that side of the support facing said butt.

8. A target apparatus including a track cable, means for securing one end of the cable, a holder including a frame comprising two side parts, means for securing the cable between the free ends of the side parts and said side parts to each other, a sheave pivotally mounted between the side parts, a support extending between the side parts to receive said sheave, and a handle lever pivotally mounted between the side parts and depending therefrom.

9. A target apparatus including a holder comprising a strip bent to form a handle at its center and with projecting ends, a pin securing said ends together, a cable secured to said pin, means for securing the other end of the cable, a support extending between the side parts of said holder, and a sheave pivotally mounted between the side parts of the holder and engaging said support.

10. A target apparatus including a holder comprising a strip bent to form a handle at its center and with projecting ends, a pin securing said ends together, a cable secured to said pin, means for securing the other end of the cable, a support extending between the side parts of said holder, a sheave pivotally mounted between the side parts of the holder and engaging said support, a handle comprising a strip of metal formed into the handle portion at its center and with projecting side parts, and means

for pivotally securing the free ends of said side parts to the side parts of said support.

11. A target apparatus including a cable track, a target carrier comprising a strip of metal constituting a base, uprights extending from said base in pairs, plates securing the members of each pair of uprights, sheaves

supported on said plates, and a U-shaped target carrier comprising branching arms having outturned feet that are secured to 10 the under side of said base to impart rigidity thereto and to support a target.

FREDERICK W. STELLING.
